UNITED STATES PATENT OFFICE

WATSON J. MILLER AND HENRY BERRY, OF BIRMINGHAM, CONNECTICUT.

SIRUP-PITCHER.

SPECIFICATION forming part of Letters Patent No. 242,019, dated May 24, 1881.

Application filed April 2, 1881. (No model.)

To all whom it may concern:

Be it known that we, WATSON J. MILLER and HENRY BERRY, of Birmingham, in the county of New Haven and State of Connecticut, have invented a new and valuable Improvement in Sirup-Pitchers; and we do hereby declare that the following is a full, clear, and exact description of the construction and operation of the same, reference being had to the annexed drawings, making a part of this specification, and to the letters and figures of reference marked thereon.

Figure 1 is a side view, partly in section. Fig. 2 is a detail view of the same, showing the 15 lip; Fig. 3, a view showing the stops.

This invention relates to improvements in sirup-pitchers.

The invention consists in a removable lip and a passage made therethrough, as set forth.

20 In the annexed drawings, A represents a pitcher having the neck a, with the internal screw-thread, a', and a stop, a², at the lower end of the thread.

B is the lip, having the flange b, with the underneath annular collar b', screw-threaded at b² to correspond with thread a', said thread b² having the stop b³ formed at its lower end. Projecting up from this flange b is an annular neck, C, forming the lip proper, for pouring out

the contents of the pitcher. Attached to this 30 neck is a curved plate, D, forming a catch, and back of this plate is an opening, d, leading into the interior of the neck C, which is hollow. On the underneath side, below flange b, this lip B has an annular projection, E, having its 35 bottom e sloping off from the side of the lip having plate D, and at its lower end having the opening e'.

Through the lip B, from opening d to opening e', is a passage, F. This lip B is screwed 40 into the neck a. The stops, coming in contact, prevent jamming.

The contents of the pitcher are poured out over the catch D, and all drip runs down this catch and through passage F and into the 45 pitcher by the opening e'.

We claim—

A pitcher the lip of which has a passage therethrough, as and for the purpose set forth.

In testimony that we claim the above we 50 have hereunto subscribed our names in the presence of two witnesses.

WATSON J. MILLER.
HENRY BERRY.
